(57) **CLAIM**

The ornamental design for a football shaped carabiner, as shown and described.

DESCRIPTION

FIG. 1 is a top perspective view of my new design for a football shaped carabiner.

FIG. 2 is a plan view of the top and bottom sides, which are mirror images, of the football shaped carabiner shown in FIG. 1

FIG. 3 is a top plan view of the football shaped carabiner in an alternate embodiment with the laces raised on the surface shown in the open condition.

FIG. 4 is a right plan view of the football shaped carabiner shown in FIG. 1

FIG. 5 is a left plan view of the football shaped carabiner shown in FIG. 1

FIG. 6 is a back elevational view of the football shaped carabiner shown in FIG. 1; and,

FIG. 7 is a front elevational view of the football shaped carabiner shown in FIG. 1.
